WILHELM MUSS, OF HANOVER, GERMANY

HEAVIER-THAN-AIR AIRCRAFT

Application filed February 11, 1931, Serial No. 514,973, and in Germany February 21, 1929.

This invention relates to heavier than air aircraft, and has for its object to provide an aeroplane, whether of the land or water type, which constantly maintains a horizontal position but is, nevertheless, capable of rising.

5 The above object is attained, according to the invention, by providing, on each side of the body of the aeroplane and in succession, three planes which are laterally arched from the body, are rotatably mounted about axes transverse to the direction of flight, and progressively widen from the front to the back of the aeroplane. An engine driven propeller is disposed on each side of the body below or in front of each plane of the foremost pair 10 of planes, and in addition two engine driven air-screws are provided, one in front of the body as a propeller, and the other above the body as a lifting screw.

15 An aeroplane constructed in the above manner may be adapted for vertical ascent and descent, and for forward and backward flight by the further provision according to the invention, of an engine driven propeller behind or below each plane of the back pair 20 of planes, and by providing above the front and rear ends of the aeroplane, obliquely disposed lifting screws which draw air from over the aeroplane, and force it longitudinally outwardly as much as possible so that the currents produced do not reach the aeroplane body.

25 The invention is illustrated by way of example in the accompanying drawings, in which:—

Figure 1 is a front view of a land aeroplane constructed according to the invention,

Figure 2 is a side view thereof,

Figure 3 is a side view of a modified construction of aeroplane according to the invention, employing an additional propeller arrangement, and

Figure 4 is a plan view, corresponding to Figure 3.

45 The aeroplane body 1 is of downwardly

directed V shape, conforming to the slope of the arched planes 5, 6, 7, 8, 9 and 10, whilst its top surface is of inverted V or roof-shape. The body 1 is provided with running wheels for use in landing on the ground, whilst it is also formed as a floating body for use as 50 a seaplane.

At the two sides of the body 1, there are rotatably mounted on axles 2, 3 and 4, disposed transversely to the direction of flight, 55 the arched planes 5, 6, 7, 8, 9 and 10, the outer ends of which are connected with the ends of the axles 2, 3 and 4, and the inner ends of which extend to the widest part of the body 1. The planes increase progressively in width from the front to the back of the aeroplane, so that each plane of the pair of planes 7, 8 is wider than each plane of the pair of planes 5, 6 and each plane of the pair of planes 9, 10 is wider than each plane 60 of the pair of planes 7, 8.

Arranged beneath or in front of the planes of the pair of planes 5, 6 are propellers 13 and 14 respectively, which are driven by engines 11 and 12 respectively, and the diameter of the propellers conforms to the curvature of the planes. Another propeller 15 is also provided at the front 16 of the body, and a further air-screw 17, disposed obliquely to the body, is provided on the 70 top of the body to act as a lifting screw. The propeller 15 and air-screw 17 are both driven by an engine 18. 19 denotes the lateral steering rudder. The planes 5 to 10 are suitably strutted to the corresponding plane axles 2, 3 and 4, and are rotatably adjustable about said axles from the pilot's seat 21 by means of rods 20.

75 The successive widening of the pairs of planes ensures that, on adjustment of the 85 planes (see Figure 2) for rising of the aeroplane, the pairs of planes 7, 8 and 9, 10, arranged behind the pair of planes 5, 6, will still present parts exposed to the action of the air thrown back by the propellers 13, 14 80

and 15. Thus, the constant maintenance of the horizontal position of the aeroplane on rising is obtained.

According to Figures 3 and 4, there are arranged beneath or in front of the pair of planes 5, 6, and beneath or behind the pair of planes 9, 10, propellers 13, 14 and 26, 27, which are driven by engines 11, 12, 24 and 25 respectively, the diameter of the propellers conforming to the curvature of the planes. The propellers 13, 14, 26 and 27 may also be arranged obliquely to the direction of flight, in which case the air pushed back by them exerts an additional action by encountering the sloping parts 28 of the body 1. With this arrangement, it is possible to drive the propellers 13, 14, 26 and 27 in common by an engine mounted in the middle of the body, whereas, in the first case, the propellers 13, 14, 26 and 27 are driven by independent engines arranged beneath or in front of the planes 5, 6, 9 and 10.

Above the aeroplane at the front and rear respectively, are provided inclined lifting screws 17 and 29 which work in opposition, so as both to draw air from above the aeroplane and force it longitudinally outwardly, whereby the air currents of said air-screws are prevented as much as possible from striking the aeroplane. In addition to the propeller 15 at the front of the body 1, auxiliary air-screws 30 and 31 are disposed with their axes transverse to the direction of flight, laterally of the middle pair of planes 7, 8. These air-screws 30 and 31 may usually, however, be omitted. For permitting backward flight to be performed, there may be provided a further air-screw 32 which corresponds inversely in its functions to the propeller 15.

In comparison with the action obtained with the construction illustrated by Figure 2, an improvement is obtained by fitting the propellers 13, 14 and 17, 29 provided in the construction illustrated by Figures 3 and 4, inasmuch as the oblique positioning of the lifting screws considerably increases, as experiments have shown, the capability of the aeroplane of rising in its forward flight.

By the further provision of the air-screws 26 and 27, it is possible, by suitably adjusting the arched planes 5 to 10, to obtain a vertical ascent and also a vertical descent, the speed of the propellers 17 and 29 being suitably regulated. For backward flight, the propeller 15 is stopped and the propeller 32 brought into action. By providing for regulation of the speed of all the propellers and air-screws, and by adjustment of the planes, the speeds of forward and backward flight, and of ascent and descent are variable.

It is also within the scope of the invention to construct the planes 5 to 10 of flat form instead of arched.

What I claim is:—

1. An aeroplane comprising in combination a body portion having propelling and lifting air-screws and driving means therefor, a longitudinal series of arched planes extending laterally on each side of said body portion, and separate propellers associated with the front planes on each side of the body, the planes successively increasing in width from front to rear of the body portion. 70

2. An aeroplane comprising in combination a body portion having propelling and lifting air-screws and driving mechanism therefor, a plurality of axles extending laterally on each side of the body in horizontally spaced relation, and a series of arched planes adjustably mounted on said axles on each side of the body portion. 80

3. An aeroplane comprising in combination a body portion having propelling and lifting air-screws and driving mechanism therefor, a plurality of axles extending laterally on each side of the body in horizontally spaced relation, a longitudinal series of arched planes adjustably mounted on said axles on each side of the body portion, and separate propellers associated with said arched planes on each side of the body. 85 90

4. An aeroplane comprising in combination a body portion having propelling and lifting air-screws and driving mechanism therefor, a plurality of axles extending laterally on each side of the body in horizontally spaced relation, a longitudinal series of arched planes adjustably mounted on said axles on each side of the body portion, and separate propellers associated with the front planes on each side of the body. 100

5. An aeroplane comprising in combination a body portion having propelling and lifting air-screws and driving mechanism therefor, a plurality of axles extending laterally on each side of the body in horizontally spaced relation, and a series of planes adjustably mounted on said axles on each side of the body portion, the planes successively increasing in width from front to rear of the body portion. 110

6. An aeroplane comprising in combination a body portion having propelling and lifting air-screws and driving means therefor, arched planes extending laterally on each side of said body portion at the level of the widest part thereof, the body being V shaped below said arched planes, and separate propellers associated with said arched planes on each side of the body. 115 120

7. An aeroplane comprising in combination a body portion having propelling and lifting air-screws and driving means therefor, arched planes extending laterally on each side of said body portion, and separate propellers associated with said arched planes on each side of the body, said propeller being 125 130

disposed below the level of said planes and being of a diameter conforming to the curvature thereof.

8. An aeroplane comprising in combination a body portion having propelling and lifting air-screws and driving means therefor, a longitudinal series of arched planes extending laterally on each side of said body portion, and separate propellers associated with the front planes on each side of the body, and also with the rear planes on each side of the body portion.

9. An aeroplane comprising in combination a body portion having propelling and lifting air-screws and driving mechanism therefor, a plurality of axles extending laterally on each side of the body in horizontally spaced relation, and a series of planes adjustably mounted on said axles on each side of the body portion, and including inclined engine driven lifting air-screws disposed above the front and rear ends of the body.

10. An aeroplane comprising in combination a body portion having propelling and lifting air-screws and driving means therefor, arched planes extending laterally on each side of said body portion, and separate propellers associated with said arched planes on each side of the body, and including inclined engine driven lifting air-screws disposed above the front and rear ends of the body.

11. An aeroplane comprising in combination a body portion having propelling and lifting air-screws and driving means therefor, a longitudinal series of arched planes extending laterally on each side of said body portion, and separate propellers associated with the front planes on each side of the body, and including inclined engine driven lifting air-screws disposed above the front and rear ends of the body.

12. An aeroplane comprising in combination a body portion having propelling and lifting air-screws and driving means therefor, a longitudinal series of arched planes extending laterally on each side of said body portion, and separate propellers associated with the front planes on each side of the body, the planes successively increasing in width from front to rear of the body portion, and including inclined engine driven lifting air-screws disposed above the front and rear ends of the body.

13. An aeroplane comprising in combination a body portion having propelling and lifting air-screws and driving mechanism therefor, a plurality of axles extending laterally on each side of the body in horizontally spaced relation, and a series of arched planes adjustably mounted on said axles on each side of the body portion, and including inclined engine driven lifting air-screws disposed above the front and rear ends of the body.

14. An aeroplane comprising in combina-

tion a body portion having propelling and lifting air-screws and driving mechanism therefor, a plurality of axles extending laterally on each side of the body in horizontally spaced relation, a longitudinal series of arched planes adjustably mounted on said axles on each side of the body portion, and separate propellers associated with said arched planes on each side of the body, and including inclined engine driven lifting air-screws disposed above the front and rear ends of the body.

15. An aeroplane comprising in combination a body portion having propelling and lifting air-screws and driving mechanism therefor, a plurality of axles extending laterally on each side of the body in horizontally spaced relation, a longitudinal series of arched planes adjustably mounted on said axles on each side of the body portion, and separate propellers associated with the front planes on each side of the body, and including inclined engine driven lifting air-screws disposed above the front and rear ends of the body.

16. An aeroplane comprising in combination a body portion having propelling and lifting air-screws and driving mechanism therefor, a plurality of axles extending laterally on each side of the body in horizontally spaced relation, and a series of planes adjustably mounted on said axles on each side of the body portion, the planes successively increasing in width from front to rear of the body portion, and including inclined engine driven lifting air-screws disposed above the front and rear ends of the body.

17. An aeroplane comprising in combination a body portion having propelling and lifting air-screws and driving means therefor, arched planes extending laterally on each side of said body portion at the level of the widest part thereof, the body being V shaped below said arched planes, and separate propellers associated with said arched planes on each side of the body, and including inclined engine driven lifting air-screws disposed above the front and rear ends of the body.

18. An aeroplane comprising in combination a body portion having propelling and lifting air-screws and driving means therefor, arched planes extending laterally on each side of said body portion, and separate propellers associated with said arched planes on each side of the body, said propellers being disposed below the level of said planes and being of a diameter conforming to the curvature thereof, and including inclined engine driven lifting air-screws disposed above the front and rear ends of the body.

19. An aeroplane comprising in combination a body portion having propelling and lifting air-screws and driving means there-

for, a longitudinal series of arched planes extending laterally on each side of said body portion, and separate propellers associated with the front planes on each side of the body, and also with the rear planes on each 5 side of the body portion, and including inclined engine driven lifting air-screws disposed above the front and rear ends of the body.

10 In testimony whereof I have signed my name to this specification.
